UNITED STATES PATENT OFFICE

CHARLES L. HEISLER, OF SCHENECTADY, NEW YORK, ASSIGNOR TO GENERAL ELECTRIC COMPANY, A CORPORATION OF NEW YORK

SOUND REPRODUCING APPARATUS

Application filed September 25, 1929. Serial No. 395,169.

My invention relates to apparatus by which sound may be reproduced electrically from a photographic sound record on a film of the motion picture type, and the object of my invention is the provision of improved supporting means for the film and for the photo-electric member associated therewith.

My invention will be better understood from the following description taken in connection with the accompanying drawings, and its scope will be pointed out in the appended claims. This application is a continuation in part of my co-pending application Serial No. 203,344, filed July 5, 1927, now

15 Patent No. 1,771,922, July 29, 1930.

Referring to the drawings, Fig. 1 is a side elevation partly in section of a portion of a reproducing apparatus involving my invention; Fig. 2 is a plan view of the same also partly in section; Figs. 3 and 4 are detail sectional views taken respectively on the lines 20 3-3 and 4-4 of Fig. 1; and Fig. 5 is a disassembled view of the photo-electric cell supporting means.

25 In the drawings, the frame 1 of the reproducing machine forms a bearing for the shaft 2 which beyond the bearing carries the film supporting drum 3. The drum, which is preferably constructed of steel, is hollow and is divided circumferentially to form a two-part structure, one part or member 4 being fixed to the shaft and the other part or member 5 being detachably secured to the outer or free end of the shaft. The film 7, of the motion 30 picture type, in its passage from the take-off reel to the take-up reel, both not shown, passes from the guide roller 8 over drum 3 to the pressure roller 9. To insure a more uniform rotation of the drum, the shaft 2 preferably 35 has a fly-wheel mounted thereon. Either the drum may be driven at the desired speed by a connection through the shaft 2 with suitable driving apparatus, such as an electric motor, or the drum and fly-wheel may be 40 driven partly or solely by the pull of the film.

The film 7 in the present example has a sound record track extending longitudinally of and adjacent one edge thereof. The space between the two drum portions 4 and 5 is approximately equal to the width of the sound track, being if anything slightly greater than the sound track. In order to increase the adhesion between the drum and the film, the fixed portion 4 of the drum is provided with the rubber tire 10 which is let into the face of 50 the drum so that its periphery is flush with the drum surface. A light beam from a suitable source, not shown, is focused by an optical system shown in part at 12 on the sound record in the form of a very narrow beam 55 which after passing through the record enters the photo-electric cell 13. By this construction the film is firmly supported on both sides of and immediately next to the sound track, thus insuring that the sound record on 60 the film shall remain at all times in the proper focus of the optical system.

Access to the photo-cell 13 is obtained by the removal of the drum portion 5 from the shaft 2. The end portion of the shaft is tapered at 15 and the boss 16 on the drum portion 5 is correspondingly tapered. Thumb nut 17 threaded on the end of shaft 2 clamps 65 the tapered portions together.

The drum not only supports the film in 70 proper focal position at the point of light interception, and by reason of the attached fly-wheel insures a high degree of uniformity of motion thereof, but also shields the photo-cell from various electrical disturbances 75 which otherwise produce objectionable noises in the reproduced sound.

Attached to the frame 1 is the support 20, a portion 21 of which is shown extending through the opening 22 of frame 1 and terminating in the contact housing 23. Detachably secured to this housing by the thumb nut 24 is the bracket 25 preferably of steel, which extends through the space between the two drum portions and has attached to it 80

the insulation block 26. This block surrounds the shaft 2 with sufficient clearance to avoid actual contact, and at one side has the recess 27 for receiving the photo-cell 13, suitable socket contacts being provided in the block for engaging the contact posts on the end of the cell. One of the connecting wires is shown embedded in the groove 28 in the bracket 25 and the other is shown enclosed in the steel tube 29 on the side of the bracket. 10 These wires terminate in the plugs 30 in the insulation block 31, and are received by socket contacts in the insulation block 32. From these socket contacts, connecting wires 33 extend into the steel transformer housing 34 from which suitable connection is made to amplifying apparatus and loud speaker or other translating device. 15

What I claim as new and desire to secure 20 by Letters Patent of the United States is:

1. In apparatus for reproducing sound from a film record, a rotatable shaft having a free end portion, a drum on said portion adapted to support a record film, said drum comprising a plurality of separate cylindrical members spaced apart axially and separately mounted on said portion, a photo-electric cell mounted within the drum and means for detachably securing the outermost member to the shaft. 25

2. In apparatus for reproducing sound from a film record, a rotatable shaft having a free end portion, a drum on said portion adapted to support a record film, said drum comprising a plurality of separate cylindrical members spaced apart axially, one of said members being fixed to the shaft, the other of said members and the shaft being tapered and means for clamping together the shaft 30 and said other member.

3. In apparatus for producing sound from a film record, a rotatably mounted shaft having a free end portion, a film supporting drum on said portion comprising a plurality 35 of separate axially spaced members, the outermost of said members being detachably secured to the shaft independently of the other member, a photo-electric cell between the shaft and the peripheral wall of the drum, a bracket extending between the drum members for supporting the cell, a support for the bracket, means for detachably connecting the bracket to the support, a conductor carried by the bracket and cooperating detachable 40 circuit connectors on the bracket and the support.

4. In apparatus for reproducing sound from a film having a sound record track thereon, a shaft, a drum for supporting the 45 film comprising a portion fixed to the shaft, a portion detachably secured to the end of the shaft and spaced from the fixed portion a distance approximately equal to the width of the sound record track, a fixed support, 50 a bracket detachably connected therewith ex-

tending through the space between the drum portions, an insulation block secured to said bracket within the drum and having a contact socket therein, a photo-electric cell in said socket extending axially between the 70 shaft and the wall of the drum, and circuit connections for said cell secured to said bracket.

In witness whereof, I have hereunto set my hand this 24th day of September, 1929. 75

CHARLES L. HEISLER.
